UNITED STATES PATENT OFFICE.

FRANK A. WOODS, OF RACINE, WISCONSIN.

DESIGN FOR A CHAIR.

SPECIFICATION forming part of Design No. 24,005, dated February 5, 1895.

Application filed December 13, 1894. Serial No. 531,734. Term of patent 14 years.

To all whom it may concern:

Be it known that I, FRANK A. WOODS, a citizen of the United States of America, residing at Racine, in the county of Racine and State of Wisconsin, have invented and produced a new and original Design for Chairs, of which the following is a specification, reference being had to the accompanying drawings, and to letters of reference marked thereon, which form a part thereof.

Figures 1 and 2 are perspective views of a chair showing my design.

The leading features of the design consist in a chair having a front panel beneath the seat portion and four corner supports or legs to which the arms of the chair are attached, said arms extending rearwardly beyond the rear legs or supports, such a chair having a back of the configuration shown.

A designates the seat of the chair; B, the panel below the same; C, the front legs, and D the rear legs.

E and F designate receptacles which are of the configuration shown to present pockets and shelves.

The specific configuration and arrangement of the parts of my design are fully shown in the accompanying drawings, and

What I claim is—

The design for a chair as herein shown and described.

In testimony whereof I affix my signature in presence of two witnesses.

FRANK A. WOODS.

Witnesses:

D. J. MOREY,
FRED PISTER.
